[57] CLAIM

The ornamental design for watch band, as shown and described.

DESCRIPTION

FIG. 1 is a top plan view of a watch band showing my new design;

FIG. 2 is a side elevational view, the opposite side being a mirror image;

FIG. 3 is a bottom plan view;

FIG. 4 is a partial top plan view of a watch band showing a second embodiment of my new design;

FIG. 5 is a partial top plan view of a watch band showing a third embodiment of my new design;

FIG. 6 is a partial top plan view of a watch band showing a second embodiment of my new design;

FIG. 7 is an end elevational; and,

FIG. 8 is an end elevational.

The views and portions not shown of the second, third and fourth embodiments are the same as those shown in FIGS. 1-3 and 7-8 the essential difference being the surface texture.
